DESIGN FOR LACE DOILY OR SIMILAR ARTICLE

Czeslawa Kowalewska, Chicago, Ill.

Application June 17, 1938, Serial No. 77,895

Term of patent 3½ years

To all whom it may concern:

Be it known that I, Czeslawa Kowalewska, a citizen of the United States, residing in the city of Chicago, county of Cook, and State of Illinois, have invented a new, original, and ornamental Design for Lace Doily or Similar Article, of which the following is a specification, reference being had to the accompanying drawing, forming a part thereof.

The drawing is a face view of a lace doily or similar article showing my new design.

The design comprises a solid circular centerpiece ornamented by radiating ribs and surrounded by a ring of open lace work, as shown.

I claim:

The ornamental design for lace doily or similar article, as shown and described.

CZESLAWA KOWALEWSKA.
